UNITED STATES PATENT OFFICE

159,493

SHOE

Max Lauer, New York, N. Y.

Application April 11, 1950, Serial No. 9,141

Term of patent 3½ years

(Cl. D7—7)

To all whom it may concern:

Be it known that I, Max Lauer, a citizen of the United States of America, residing in New York, county of New York, and State of New York, have invented a new, original, and ornamental Design for a Shoe, of which the following is a specification, reference being had to the accompanying drawing, forming part thereof.

The figure on the drawing is a perspective view of a shoe showing my new design. The opposite side presents substantially the same appearance as that shown.

I claim:

The ornamental design for a shoe, substantially as shown and described.

MAX LAUER.
